WILLIAM GRANT FISKE, OF PURFLEET, ENGLAND.

APPARATUS FOR THE TREATMENT OF PAPER-STOCK.

1,273,841.

Specification of Letters Patent. Patented July 30, 1918.

Application filed February 24, 1917. Serial No. 150,845.

To all whom it may concern:

Be it known that I, WILLIAM GRANT FISKE, a citizen of the United States of America, and resident of Purfleet, Essex, 5 England, have invented certain new and useful Improvements in and Apparatus for the Treatment of Paper-Stock, of which the following is a specification.

This invention relates to improvements 10 in, and in apparatus for, the treatment of paper stock such as waste paper, wood pulp, and similar materials which require to be soaked and at least partially disintegrated as a preliminary stage in their manufacture 15 or re-manufacture into paper, cardboard, and the like; the object of the invention being to facilitate the operation and reduce its cost, by enabling the treatment to be carried on continuously and with a considerably less expenditure of mechanical power 20 than heretofore.

According to the present invention the material to be treated is fed along with a limited quantity of water (or other suitable 25 liquid) in a stream, preferably continuous, to a confined channel wherein the mixture of solid and liquid is caused to follow, on its way to the point of discharge, a course 30 of such length as to afford time for thorough soaking of the permeable portions of the material, said channel receiving motion of such character as to impart to the material a tumbling movement adapted, in co-operation with the soaking process, to bring 35 about disintegration and partial reduction to a pulpy consistency of all but the more resistant portions of the material, without the necessity of employing positively-acting 40 mechanical devices for tearing the material asunder. In addition, those portions of the material which yield less readily to the disintegrative process are automatically retained within the channel or even returned, to an earlier point in its course, until either 45 sufficiently soaked and disintegrated or (it may be) finally rejected.

The quantity of water (or other liquid) employed should be limited to what is required for effecting such thorough soaking 50 of the material as is necessary in order to render the masses of material capable of easy disintegration and reduction to a pulpy consistency, it being undesirable to associate with the solid matter such an excess of 55 liquid as would require subsequent concentration in order to prevent loss of the fibrous

particles or other valuable substances held in suspension within the liquid.

It is to be observed that the process of the present invention is not a washing process, but rather a process of digestion; that is to say, the process does not aim at effecting separation between the bulk of the material and any impurities therein, inasmuch as practically all the solid material which is subjected to treatment is required to be retained and used, along with the greater part of the liquid employed in effecting the operation of soaking and disintegration. Hence the method of treatment is distinct 70 from any continuous process of washing heretofore proposed for the treatment of paper-making or other materials, wherein the solid matter is caused to travel in one direction and the washing water in the opposite direction so as to carry off the impurities which become separated from the valuable solids.

The apparatus employed for carrying out the present invention is of what may be termed the rotary helix type with baffles or buckets, comprising a rotary horizontal drum having an open helical channel on its inner periphery so that solid material fed into the drum at one end will, by the revolution of the drum, be caused to travel to the opposite end, whereat it is discharged; the helical channel being spanned at intervals by baffles adapted to arrest the material and carry it around toward the upper side 90 of the drum whence it is allowed to fall back. Hence the apparatus which I employ bears a general resemblance to apparatus of the same type which has been proposed for use in the operation of continuously washing (as distinct from disintegrating) materials used in paper-making; but it differs therefrom in respect of the construction of the baffles, hereinafter referred to as "gates", which are designed with an especial view to 95 promoting the disintegrative process without unduly prolonging the stay of the material within the drum, while provision is also made for facilitating the regulation of the quantity of liquid associated with the 100 solid matter under treatment.

In the accompanying drawings, which illustrate one form of apparatus for carrying out the invention, Figure 1 is a side elevation and Fig. 2 an axial vertical section of 110 the apparatus; Fig. 3 is an elevation viewed from the feed end of the drum; Fig. 4 is a

cross section at a point toward the middle of the length of the drum, viewed in the same direction as Fig. 3; and Fig. 5 is a similar cross section near the outlet end of 5 the drum, showing different forms of "gates."

11 is the hollow drum, which is cylindrical in form with its longitudinal axis horizontal, the inlet end of the drum being 10 closed by a diaphragm 12 while the outlet end 13 is open and has a flaring lip 14. The diaphragm 12 has a central circular opening through which the material to be treated is fed, along with liquid, to the drum by 15 means of a chute 15 surmounted by a hopper 16. The drum is supported so as to be capable of revolving upon pairs 17, 18 of rollers peripherally grooved to engage circumferential ribs 19, 20 on the exterior of 20 the drum; continuous rotary motion (in the direction of the arrows α) being imparted to the drum by means of a shaft 21 carrying a worm 22 which meshes with a circumferential ring 23 of teeth on the drum.

25 The drum is furnished upon its internal periphery with a helical partition or flange 24 which extends inward from the wall of the drum so as to provide between the convolutions an open channel 25 winding from 30 end to end of the drum. At intervals this channel is spanned by "gates" such as have already been referred to. Several examples are illustrated in the drawings, all those shown being constituted by plates extending 35 from side to side of the channel and from the wall of the drum through a greater or less proportion of the depth of the channel. The plates constituting the gates are shown as of various forms. In Fig. 2, those illustrated at 26, 27, 28, 29, and 30 have serrated edges, the plates themselves being, in successive convolutions, of progressively increasing radial depth, and the depth of the serrations also increasing progressively in 40 successive convolutions, while the plates extend in planes parallel to the axis of the drum in the case of the gates shown at 26, 27 and 30, but in planes oblique to said axis in the case of the gates shown at 28 and 29. 45 The gates shown at 31, which extend to the full radial depth of the channel, have plain edges, and lie in planes parallel to the axis of the drum. The gates shown at 32, which extend the full radial depth of the channel, 50 have plain edges, but lie in planes oblique to the axis of the drum. The gates shown at 33, 34 and 35 are similar to those shown at 32 except that whereas those shown at 32 are devoid of apertures, those shown at 33 55 have slots extending in the direction of the width of the channel while those at 34 and 35 have slots which extend in the direction of the depth of the channel but at less distances apart in successive convolutions. In 60 Fig. 4 the four gates illustrated extend ra-

dially of the drum through different distances from its wall, that shown at 36 being the full depth of the channel while of the succeeding gates 39 is of about half that depth, 38 is somewhat deeper, and 37 is of 70 about three-fourths the depth of the channel. In Fig. 5, of the four gates illustrated, 40 and 41 are inclined tangentially with reference to the axis of the drum so as to be adapted to act more efficiently as buckets, 75 while 42 and 43 are curved for the same purpose.

The object of providing some of the gates, as for example those at 26, 27, 28, 29, and 30, with serrated edges is to promote the disintegrative operation by causing the larger masses of material to become, so to speak, combed-out in their passage over the serrations and also broken-up by falling upon the serrated edges after being lifted by the 80 action of other gates. The serrated gates also act to some extent as strainers to retard temporarily the progress through the drum of the larger and heavier masses of material while allowing the supernatant liquid to 85 flow on continuously and carry forward with it such smaller particles of material as may have become separated from the larger masses. The apertured gates, as for example those at 33, 34 and 35, are likewise 90 designed to act as strainers whereby to detain the larger masses of material while giving passage to the liquid and to such smaller particles of material as are carried along therewith.

In the case of gates which are inclined obliquely with reference to the axis of the drum (as in the examples shown at 28, 29, and 32 to 35), the inclination is such that the plate constituting the gate forms toward 95 its rear end, in conjunction with the adjacent helical flange 24, an approximately V-shaped pocket or bucket adapted to deliver its contents rearward into the previous convolution of the channel, so as to cause the 100 material taken up by these gates to be retarded in its advance lengthwise of the drum.

If desired, more than one helical flange 105 may be provided, in which case the channel would have the character of a double-threaded or multiple-threaded screw. Such an arrangement is illustrated in Fig. 2, wherein the channel 25 forms a double helix. Moreover, the inclination or advance of 110 the helical flange, and therefore also of the channel, may if desired be non-continuous, the channel extending throughout (say) the greater part of a convolution in one plane 115 perpendicular to the axis of revolution, and the inclined portion or portions occupying a relatively small part or parts of a convolution. Furthermore, the pitch or inclination and (or) the depth of the helical flange, 120 and therefore also of the channel, may if de- 125

sired be increased or otherwise varied from end to end of the drum or at any required point or points in its length.

It will be observed that whereas in apparatus designed to effect a continuous process of washing, the solid matter and the water whereby it is purified are made to travel respectively in opposite directions (the quantity of water used being virtually unlimited), in the apparatus of the present invention all the liquid travels in the same direction as the solid matter, and is limited in quantity as already stated. Hence all the liquid required may be introduced along with the material by way of the chute 15, but in order to enable the quantity of water (or other liquid) relatively to the quantity of solid material to be subsequently increased if desired, a water supply pipe 44 extends from the outlet end 13 lengthwise of the space within the drum and is provided at 45 and 46 with outlets controlled by valves 47 and 48 the spindles of which are prolonged beyond the outlet end 13 of the drum and furnished with suitable hand-wheels 49 and 50.

It is to be understood that the drum may be of any length and diameter, and may be either cylindrical or of other shape (such as polygonal) in cross-section. It may also, obviously, be supported and rotated by other means than those illustrated in the drawings.

The stream of material falling from the outlet end of the drum may be screened to effect the final separation of any lumps or masses of solid which happen to pass all the gates, and such lumps or masses may if desired be returned to the chute by means of a continuously-driven bucket-conveyer or other convenient apparatus.

The water or other liquid fed into the drum, whether at the inlet end thereof or at any intermediate point or points in its length, may (and as a rule preferably would) be warm; and the liquid may consist of or contain a solution of any substance adapted to promote the disintegration or other preparatory treatment of the solid material, or to extract therefrom any constituent which it may be desirable to remove prior to the material being subjected to the further processes incidental to manufacture or re-manufacture.

55 I claim—

1. The method of treating paper stock by a continuous soaking and disintegrative process without the employment of positively-acting mechanical tearing devices, which consists in causing the material, along with liquid, to pass in a stream through a confined channel of such length as to afford time for thorough soaking of the permeable portions of the material, said channel receiving motion of such character as to im-

part to the material a tumbling movement adapted, in coöperation with the soaking process, to bring about disintegration and partial reduction to a pulpy consistency of all but the more resistant portions of the material.

2. An apparatus for treating paper stock comprising a rotatable drum, an inwardly open helical channel located upon the interior surface of said drum and means in said channel whereby the material is carried along and tumbled back.

3. An apparatus for treating paper stock comprising a rotatable drum, an inwardly open helical channel located upon the interior surface of said drum and baffles of progressively increasing radial depth located in said channel at spaced intervals.

4. An apparatus for treating paper stock comprising a rotatable drum, an inwardly open helical channel located upon the interior surface of said drum and baffles located in said channel at spaced intervals and having their inner edges serrated.

5. An apparatus for treating paper stock comprising a rotatable drum, an inwardly open helical channel located upon the interior surface of said drum and baffles located in said channel at spaced intervals and having their inner edges serrated, the serrations increasing progressively in depth in successive baffles.

6. An apparatus for treating paper stock comprising a rotatable drum, an inwardly open helical channel located upon the interior surface of said drum and baffles of progressively increasing radial depth located in said channel at spaced intervals and having their inner edges serrated, the serrations increasing progressively in depth in successive baffles.

7. An apparatus for treating paper stock comprising a rotatable drum, an inwardly open helical channel located upon the interior surface of said drum and apertured baffles located in said channel at spaced intervals.

8. An apparatus for treating paper stock comprising a rotatable drum, an inwardly open helical channel located upon the interior surface of said drum and baffles located in said channel at spaced intervals and provided with elongated apertures extending in the direction of the width of said channel.

9. An apparatus for treating paper stock comprising a rotatable drum, an inwardly open helical channel located upon the interior surface of said drum and baffles located in said channel at spaced intervals and each provided with a plurality of elongated apertures extending in the direction of the depth of said channel.

10. An apparatus for treating paper stock comprising a rotatable drum, an inwardly open helical channel located upon the in-

terior surface of said drum and baffles located in said channel at spaced intervals and each provided with a plurality of elongated apertures extending in the direction of the depth of said channel, the spaces between adjacent apertures in successive baffles decreasing in dimensions.

11. An apparatus for treating paper stock comprising a rotatable drum, an inwardly open helical channel located upon the interior surface of said drum and baffles located in said channel at spaced intervals, said baffles being inclined tangentially with reference to the axis of the drum.

12. An apparatus for treating paper stock comprising a rotatable drum, an inwardly open helical channel located upon the interior surface of said drum and baffles located in said channel at spaced intervals, said baffles being curved in a direction transverse to the axis of said drum.

13. An apparatus for treating paper stock comprising a rotatable drum, an inwardly open helical channel located upon the interior surface of said drum and baffles lo-

cated in said channel at spaced intervals, said baffles extending in planes oblique to the axis of the drum.

14. An apparatus for treating paper stock comprising a rotatable drum, an inwardly open helical channel located upon the interior surface of said drum, a plurality of baffles located in said channel at spaced intervals and having their inner edges serrated, a plurality of intermediate baffles in said channel and additional baffles in said channel provided with apertures.

15. An apparatus for treating paper stock comprising a rotatable drum, an inwardly open helical channel located upon the interior surface of said drum, means whereby a supply of liquid and material may be introduced into said drum, means in said channel whereby the material is carried along and thrown back and means whereby additional liquid may be introduced into said drum at one or more intermediate points.

WILLIAM GRANT FISKE.
